United States Patent Office

Des. 180,339

Patented May 21, 1957

180,339

BOX HOLDING TRAY

Samuel Pavelle, White Plains, N. Y., assignor, by mesne assignments, to Technicolor New York Corporation, a corporation of Delaware

Application March 22, 1955, Serial No. 35,161

Term of patent 14 years

(Cl. D58—13)

Fig. 1.

Fig. 2.

Figure 1 is a perspective view of a box holding tray showing my new design; and

Figure 2 is a sectional view of the same taken on substantially the plane of line 2—2 of Figure 1.

The characteristic features of my design for the tray disclosed reside in the ribbing arranged as shown.

I claim:

The ornamental design for a box holding tray, substantially as shown and described.
